CLAIM

The ornamental design for an RFID reader, as shown and described.

DESCRIPTION

FIG. 1 shows a front perspective view of an RFID reader according to an embodiment;

FIG. 2 shows a front perspective view thereof attached to a touchscreen;

FIG. 3 shows a front elevation view thereof;

FIG. 4 shows a rear elevation view thereof;

FIG. 5 shows a left elevation view thereof;

FIG. 6 shows a right elevation view thereof;

FIG. 7 shows a right elevation view thereof attached to a touchscreen;

FIG. 8 shows a top plan view thereof; and,

FIG. 9 shows a bottom plan view thereof.

The broken line showing of the touchscreen is included for the purpose of illustrating environment and forms no part of the claimed design.

1 Claim, 5 Drawing Sheets
